[57] CLAIM

The ornamental design for a combined cabinet and paper roll holder, as shown and described.

DESCRIPTION

FIG. 1 is a perspective view of a combined cabinet and paper roll holder showing my new design;

FIG. 2 is a bottom plan view thereof;

FIG. 3 is a left side elevational view thereof, the right side being a mirror image.

FIG. 4 is a front elevational view thereof; and

FIG. 5 is a rear elevational view thereof.
